(57) **CLAIM**

The ornamental design for a reusable cable reel as shown and described.

DESCRIPTION

FIG. 1 is a front, top, right side perspective view of a reusable cable reel;

FIG. 2 is a rear, top, right side perspective view thereof;

FIG. 3 is a front, top, right side exploded view thereof;

FIG. 4 is a right elevational view thereof;

FIG. 5 is a left elevational view thereof;

FIG. 6 is a top plan view thereof;

FIG. 7 is a bottom plan view thereof;

FIG. 8 is a front elevational view thereof; and,

FIG. 9 is a rear elevational view thereof.

The broken lines in the drawings depict portions of the reusable cable reel that form no part of the claimed design.

1 Claim, 9 Drawing Sheets
